ATTORNEY

UNITED STATES PATENT OFFICE

HAROLD J. MOORE, OF MIDDLETOWN, CONNECTICUT

BUFFER FOR CLEANING AND SIMILAR TOOLS

Application filed October 19, 1926. Serial No. 142,583.

My invention relates to the class of devices that are employed to prevent marring of polished or finished surfaces, as furniture, baseboards, etc., and an object of my invention, 5 among others, is the provision of a device of this class that shall be particularly efficient for the purpose for which it is intended.

One form of buffer embodying my invention and in the construction and use of which 10 the objects herein set out, as well as others, may be attained is illustrated in the accompanying drawings, in which—

Figure 1 is a view of a cleaning tool provided with my improved buffer.

15 Figure 2 is a view, scale enlarged, of a fragment of my improved buffer.

Figure 3 is a view in cross section through the same.

Figure 4 is a view in section on plane 20 noted by the dotted line 4—4 of Figure 5.

Figure 5 is a view in section on plane 25 noted by the dotted line 5—5 of Figure 4.

The scale in Figures 4 and 5 is greatly exaggerated.

30 A common form of cleaning tool employed at the present time, is of the type known as a "pneumatic cleaning tool" and in the use of such devices upon floors and similar places it is essential that means be provided to prevent the marring of furniture, baseboards, and other parts by contact with such tools in their operation. Various forms of buffers have been employed, such as those of felt or similar soft material or rubber in various 35 forms. These have not proved highly satisfactory for the reason that they will soon become inefficient by reason of stretching so that they will not be retained in place, or by reason of so much "give" that the tool may be 40 brought into contact with the finished surfaces.

It is a purpose of my invention to provide 45 a structure that, while having the necessary elastic qualities, will enable it to endure for a long period, yet at the same time have the necessary features requisite for a buffer to prevent marring of polished or other finished surfaces. Such a structure is shown in the accompanying drawings, in which I have illustrated my improved buffer in connection

with a cleaning tool denoted generally by the numeral 6. The head 7 of this tool is provided with a groove 8 in which my improved buffer 9 is located.

This buffer is composed of a combination 55 of threads suitable for buffer purposes and threads for imparting elasticity to the structure. Such a structure may consist of weaves of various sorts, but a weave that I have found particularly adapted for this purpose comprises one embodying the characteristics of what is known as a box weave, and which weave I have adapted for my purpose by incorporating the elastic threads as hereinbefore mentioned, together with means for 60 maintaining the position of such threads and thereby preserving the form of the strip from which the buffer is made.

This fabric comprises warp threads 10 and 65 weft threads 11 which may be woven in many different ways to accomplish my purpose, my invention embodying elastic threads 12, which will generally consist of rubber, comprising 70 a part of the warp. These elastic threads may vary in number and in arrangement, as 75 may be desired, in the form herein shown there being two layers of such threads extending substantially across the strip. In order to prevent these elastic threads from distorting the strip, or, in other words, to maintain the 80 form of the strip, I provide holding threads 13 that are passed preferably across the strip in the direction of depth thereof. These threads may be arranged in various ways, an arrangement which I have found satisfactory 85 comprising a holding thread located between each of the vertical rows of elastic threads 12, which rows in the present instance each have two threads and which holding threads are anchored to the weft threads in any suitable manner, as by passing the holding 90 threads entirely through the fabric or strip, between the warp threads 10, and over and between the filling or weft threads 11, and as shown especially in Figures 4 and 5 of the 95 drawings.

As hereinbefore stated the general weave 100 may be of many different types and the elastic threads and holding threads therefor comprising my contribution to the art may be ar-

ranged in different ways, my invention embodying the incorporation of the elastic threads for imparting resiliency to the strip and the holding threads for maintaining the elastic threads in position and thereby maintaining the form of the strip, especially in cross section, that herein shown providing a strip of substantially rectangular form in cross section.

10 In accordance with the provisions of the patent statutes I have described the principles of operation of my invention, together with the articles which I now consider to represent the best embodiment thereof, but I desire to have it understood that the article shown is only illustrative and that the invention may be carried out by other means and applied to uses other than those above set out.

I claim—

20 1. A buffer strip comprising warp and weft threads woven into flat tubular formation with the warp threads omitted at the edges in the warp plane of the elastic threads, a double layer of elastic threads woven into the bore of said formation, and holder threads separate from the warp threads woven through the strip in parallelism with the warp threads and spanning on the surfaces of the strip a different number of weft threads than the span of the warp threads.

2. A buffer strip comprising warp and weft threads woven into double ply tubular formation, a double layer of elastic threads woven into the bore of said formation, and holder threads separate from the warp threads woven through the strip between the elastic threads in parallelism with the warp threads but spanning in each ply a different number of weft threads than the span of the warp threads.

HAROLD J. MOORE.
